UNITED STATES PATENT OFFICE.

CHARLIE BION STOUGH, OF CRESTON, IOWA.

THILL-COUPING.

SPECIFICATION forming part of Letters Patent No. 609,477, dated August 23, 1898.

Application filed October 6, 1897. Serial No. 654,231. (No model.)

To all whom it may concern:

Be it known that I, CHARLIE BION STOUGH, a citizen of the United States, residing at Creston, in the county of Union and State of Iowa, have invented certain new and useful Improvements in Thill-Couplings; and I do hereby declare the following to be a full, clear, and exact description of the invention, such as will enable others skilled in the art to 10 which it appertains to make and use the same.

My invention has relation to certain new and useful improvements in thill-couplings, and relates more particularly to a form of coupling designed to insure a reliable union 15 between the parts, as will be hereinafter fully specified, and illustrated in the accompanying drawings, made a part of this application.

The object, therefore, of my invention may be said to consist in providing a safety appliance for carriages and other vehicles for which such a coupling is desirable.

In the accompanying drawings, Figure 1 is a perspective view of my invention complete, showing the several parts separated, ready 25 to be assembled in their respective positions. Fig. 2 is a side view of my invention complete. Fig. 3 is a side view of the locking-bolt and rib. Fig. 4 is a sectional view taken on a line with the inner surface of one of the 30 jaws of the clip.

Briefly stated, my invention consists in providing a peculiar form of locking-bolt and a reserve bolt and a hook-like termination formed upon the iron connected to the shaft 35 or pole.

Referring in detail to the several features involved in my invention, 1 is the clip employed to provide connection with the axle, and is constructed in the usual or any preferred way, while integrally formed with said clip or otherwise connected thereto are the vertically-disposed jaws 2 and 3, lying substantially parallel with each other and a sufficient distance apart to accommodate between 45 them the usual tubular body 4, connected to the shaft or pole in the usual manner, as by the integrally-formed flange or lip 5, designed to be bolted to said shaft or pole.

Integrally formed with the tubular body 4 50 is the rearwardly downwardly-extending hook-section 6, designed to partly encircle, yet lie out of contact with, the reserve bolt 7,

permanently secured at either end to the jaws 2 and 3.

The circular opening 8, extending through 55 the tubular body 4, is provided near its upper side with the continuous recess or slot 9, while each of the jaws are provided near their forward ends with the circular openings 10, preferably of the same diameter as the opening 8. 60

Each of the openings 10 is provided upon its upper sides and on line with each other with the slot or recess 11, coinciding in size, but not in normal position, with the recess 9, formed in the opening 8, and it will be apparent that by sufficiently elevating the shaft or pole the recesses 9 and 11 may be brought into registration with each other, when the bolt 12 (more clearly shown in Figs. 1 and 3) may be placed in position, so that the rib 13 70 formed thereon will freely pass through the recess 11 and be received by the recess 9, when by lowering the shaft or pole, to which the tubular body is connected, the recess 9 will be moved downward out of registration 75 with the recess 11, and thereby rotate the bolt 12 and bring the rib 13 downward out of registration with the recess 11, resulting in reliably holding said bolt against longitudinal movement until the shaft or pole is again elevated. When the tubular body 4 is thus locked in position between the jaws by means of the bolt 12, the hook-section 6 is entirely 80 out of contact with the reserve bolt 7, and the latter will not have any office to perform 85 until the bolt 12 is destroyed by wear, when the hook-section 6 will engage the bolt 7, and thereby insure against the serious results usually following the casual displacement of the bolt employed to hold the parts in union. 90

In Figs. 2 and 4 I have shown the normal position of the hook and reserve bolt, and it will be readily apparent that the shaft or pole may be freely used in the usual manner without in any way interfering with said hook or 95 bolt.

Having thus fully set forth the construction, advantages, and use of my improved coupling and safety appliance, what I claim as new, and desire to secure by Letters Patent, is—

In thill-couplings, a bifurcated clip having a perforation near each of its outer ends and a fixed reserve bolt in the rear of and lower

than said perforations, an attachment for
thills having an enlarged perforated central
portion and a hooked rearward end and
means to unite the clip and attachment
5 whereby the hooked end will extend around
but not in contact with the reserve bolt, all
combined as set forth.

In testimony whereof I affix my signature
in presence of two witnesses.

CHARLIE BION STOUGH.
